UNITED STATES PATENT OFFICE

142,552

DESIGN FOR A CLOCK

Homer Allen Frost, Jr., Tucson, Ariz.

Application August 31, 1944, Serial No. 115,152

Term of patent 14 years

(Cl. D42—7)

To all whom it may concern:

Be it known that I, Homer Allen Frost, Jr., a citizen of the United States, residing at Tucson, in the county of Pima and State of Arizona, have invented a new, original, and ornamental Design for a Clock, of which the following is a specification, reference being had to the accompanying drawing, forming part thereof.

In the drawing:

Figure 1 is a front elevational view of a clock showing my new design.

Figure 2 is a side elevational view of the clock.

Figure 3 is a developed view of the base of the clock case.

I claim:

The ornamental design for a clock, as shown and described.

HOMER ALLEN FROST, JR.
